WILLIAM J. HALE, OF ASHLEY, ILLINOIS.

Letters Patent No. 88,957, dated April 13, 1869.

IMPROVEMENT IN CHURN-DASHER.

The Schedule referred to in these Letters Patent and making part of the same.

To all whom it may concern:

Be it known that I, WILLIAM J. HALE, of Ashley, in the county of Washington, and State of Illinois, have invented a new and valuable Improvement in Churn-Dashers; and I do hereby declare that the following is a full, clear, and exact description of the construction and operation of the same, reference being had to the annexed drawings, making a part of this specification, and to the letters and figures of reference marked thereon.

Figure 1 of the drawings is a sectional view of my churn, and

Figure 2 is a view of the bottom thereof.

My invention relates to that class of churning in which an upright staff is used by the hands of the operator; and

The improvement consists in adjusting, over the ordinary dasher and around the staff, a perforated cylinder, that shall be left open and unfastened at the bottom, but closed at the top, leaving only a sufficient opening therein for the movements of the dasher-staff up and down.

The letter A, of the drawings, represents the ordinary churn, or jar, in which my improvement is used;

Letter B is the dasher-staff;

Letter C is the dasher; and

Letter H is the perforated cylinder above mentioned.

I construct this cylinder with apertures, or perforations, one-fourth of an inch in diameter and half an inch apart. Its height is always adjusted to the height of the fluid to be churned, the rule being, that in all cases its top must rise above such fluid, and never be immersed therein.

The lower end of this cylinder is never fastened to the churn-bottom, but is allowed to sit loosely thereon.

In actual use, the milk or cream is forced back and forth through the apertures of the cylinder H with great rapidity, thereby breaking the caps that enclose the butter, and releasing the same.

By allowing the cylinder to remain unfastened, I am enabled to remove and clean the same without difficulty.

What I claim as my invention, and desire to secure by Letters Patent, is—

A churn, having jar A, dasher-staff B, dasher C, and removable perforated cylinder H, constructed and arranged substantially as specified.

In testimony that I claim the above, I have hereunto subscribed my name, in the presence of two witnesses.

W. J. HALE.
